ICE SHIELD FOR AN AUTOMOBILE WINDOW

Louis A. Gorgei, General Delivery,
North Jackson, Ohio 44451

Filed Jan. 29, 1968, Ser. No. 10,389

Term of patent 14 years

(Cl. D14—6)

FIGURE 1 is a perspective view of the ice shield for an automobile window showing the inner side, the upper edge, and one outer side thereof; and

I claim:

The ornamental design for an ice shield for an automobile window, as shown.
